UNITED STATES PATENT OFFICE

99,578

DESIGN FOR A NURSERY ROCKING CHAIR OR SIMILAR ARTICLE

David W. Lynch, Lancaster, Pa.

Application March 13, 1936, Serial No. 61,614

Term of patent 14 years

To all whom it may concern:

Be it known that I, David W. Lynch, a citizen of the United States, residing at Lancaster, in the county of Lancaster and State of Pennsylvania, have invented a new, original, and ornamental Design for a Nursery Rocking Chair or Similar Article, of which the following is a specification, reference being had to the accompanying drawing, forming part thereof.

The figure is a perspective view of the nursery rocking chair showing my design.

The distinctive feature of the design consists in the pair of panels shown in full lines.

I claim:—

The ornamental design for a nursery rocking chair or similar article, as shown and described.

DAVID W. LYNCH.
